DESIGN FOR A CIGARETTE CONTAINER

William Stavenhagen, Union City, N. J.

Application April 18, 1940, Serial No. 91,745

Term of patent 7 years

To all whom it may concern:

Be it known that I, William Stavenhagen, a citizen of the United States of America and a resident of Union City, county of Hudson, State of New Jersey, have invented a new, original, and ornamental Design for a Cigarette Container, of which the following is a specification, reference being had to the accompanying drawing, forming a part thereof, in which

Fig. 1 is a perspective view of the container showing my new design in closed position; and

Fig. 2 is a perspective view thereof in open position.

I claim:

The ornamental design for a cigarette container, as shown.

WILLIAM STAVENHAGEN.
